CLAIM

The ornamental design for a cable, as shown and described.

DESCRIPTION

FIG. 1 is a right perspective view of a cable showing our new design, wherein the break lines indicate indeterminate length;

FIG. 2 is a left perspective view of a cable showing our new design, wherein the break lines indicate indeterminate length;

FIG. 3 is a top plan view thereof, wherein the break lines indicate indeterminate length;

FIG. 4 is a bottom plan view thereof, wherein the break lines indicate indeterminate length;

FIG. 5 is a right side elevation view thereof, wherein the break lines indicate indeterminate length;

FIG. 6 is a left side elevation view thereof, wherein the break lines indicate indeterminate length;

FIG. 7 is a front elevation view thereof; and,

FIG. 8 is a rear elevation view thereof.

The elements depicted in broken lines are not part of the claimed design. The appearance of any portion of the article between the break lines forms no part of the claimed design.
